D. N. Duzack,
Operating Supply-Pipe Locks.
 No 26,975 Patented Jan. 31, 1860.

UNITED STATES PATENT OFFICE.

DANIEL N. DUNZACK, OF SALEM, MASSACHUSETTS.

METHOD OF OPERATING STOP-COCKS.

Specification of Letters Patent No. 26,975, dated January 31, 1860.

To all whom it may concern:

Be it known that I, DANIEL N. DUNZACK, of Salem, in the county of Essex and State of Massachusetts, have invented a new and 5 Improved Lever for Turning Faucets in Pipes, so that They May be Conveniently Operated; and I do hereby declare that the following is a full and exact description.

My invention consists in a lever B, as seen 10 at Figure 1, and is formed in two parts that it may be lengthened or shortened, as the case may require, and is fastened together with clasps, Fig. 1, and is kept elevated by a screw K, which passes through one 15 of the parts into the other and is behind weight G, and near its top and must be turned back before the parts can be separated.

At the top of lever B, is a hollow trans- 20 verse head A, Fig. 1. At the lower end of lever B, is secured a beveled cog wheel P, which intersects with a larger beveled cog wheel F, there is a forked coupling I, Fig. 4, the square shank of which passes up 25 through cog F. The forks connect cog F with the handle of faucet L, which passes through pipe N, Fig. 1. When lever B, is turned to the right or left side of pipe N, the cogs P, and F, turn the faucet L, and let 30 the water on or off from the small pipe N, Fig. 1.

In the hollow of head A, Fig. 1, there is a 35 slide O, Fig. 2, which fits loosely in said head A, and when lever B, is canted from its center, the slide O, Fig. 2, will pass down to the lowest end of said head A.

There is a toggle Y, Fig. 3, which passes 40 through slide O, which has a notch and a hole in it for that purpose. Toggle Y, has a base which corresponds with the notch cut in slide O. Head A, is provided with two flanges T, T, at the top, upon the inside. Slide O, passes under the flanges, T, T, the top part of toggle Y, passes through slide O, 45 up between the two flanges T, T, sufficiently far enough to admit a string or wire being attached to it, and slides on the bottom of the hollow in head A. There is a pin I at each end of head A, which prevents slide O, 50 from dropping out of the ends of head A. There is a weight G, the use of which will presently be explained.

The mode of operation is as follows, when the water is to be let into the small pipe

from the main one X, lever B, being canted 55 to the right side and slide O, being at its lower end, one end of the wire is passed through a pulley secured directly over the faucet in the small pipe and fastened to the outer end of toggle Y, which is in the head 60 of A, Fig. 1. The other end of the string may be carried to any part of the house. When the wire is pulled, the upper end of toggle Y, will be canted toward the wire, consequently its base, which rest on the bottom of the hollow of head A, will lift one 65 end of slide O, and cause it to pinch against the two flanges T, T, which will prevent its slipping toward the wire, at the same time shaft G, will cause lever B, to move in a 70 prescribed circle, and in this manner lever B, is drawn up by the wire or string beyond its center, and that part of lever B, which has the weight attached to it, having 75 been previously sufficiently elevated, to overcome the power required to turn the faucet, weight G, will carry lever B, down upon the opposite side from which it started, and when the wire is slackened, slide O, will pass 80 down to the lower end of head A, and is again ready for drawing the lever to the other side. In this way the faucet in the cellar may be turned to let the water into the small pipe, or let it out through the waste 85 which will prevent its freezing, in the pipe, or having the water injured by its long standing in the lead, with as much facility as it can by the faucet in the sink, without the necessity of going into the cellar in order 90 to turn it. Lever B, is fastened to the main 95 pipe X with a clasp V, which is tightened with a wedge Z that it may be turned to any angle that may be required to connect it with the handles of the small pipes, substantially as herein shown and described.

I do not claim either of the devices separately considered, but

What I claim and desire to secure by Letters Patent is—

The arrangement and combination of the 100 several parts when arranged and combined as herein described, for the purposes set forth.

D. N. DUNZACK.
